UNITED STATES PATENT OFFICE.

JOHN V. MACDONALD, OF NEWTON CENTER, MASSACHUSETTS.

DELIVERY-WAGON.

SPECIFICATION forming part of Letters Patent No. 727,817, dated May 12, 1903.

Application filed October 10, 1902. Serial No. 126,742. (No model.)

To all whom it may concern:

Be it known that I, JOHN V. MACDONALD, a citizen of the United States, residing at Newton Center, in the county of Middlesex and State of Massachusetts, have invented certain new and useful Improvements in Delivery-Wagons; and I do hereby declare the following to be a full, clear, and exact description of the invention, such as will enable others skilled in the art to which it appertains to make and use the same.

This invention relates to delivery-wagons for grocers and others; and it consists in the novel construction and combination of the parts hereinafter fully described and claimed.

In the drawings, Figure 1 is a side view of the body of a wagon constructed according to this invention. Fig. 2 is a cross-section through one of the curtain-rollers.

A is the frame of the body portion of a wagon, B is its top, and b represents the end uprights which support the top. B' represents intermediate uprights provided with bent portions b'. Spring curtain-rollers C are journaled in the end uprights and are provided with curtains c, which form the sides of the wagon-body when pulled down. The curved portions b' of the intermediate uprights permit the curtain-rollers C to extend between the end uprights. The rear end uprights are provided with bent portions d, and D is a spring curtain-roller provided with a curtain d', which forms the end of the wagon-body when pulled down. The roller D is journaled in the rear end uprights under the end

portions of the side rollers, the bent portions d being provided to permit the rollers to be arranged in this manner.

The spring-rollers are of any approved construction, but are provided with stronger 40 springs than window-curtain rollers. The rollers are journaled as close to the top as possible, and the top is provided with flaps e, which overlap the rollers and conceal them from view.

What I claim is—

1. The combination, with a wagon-body, of end uprights, spring curtain-rollers journaled in the said end uprights at the sides of the wagon-body, intermediate uprights provided with curved portions to clear the said rollers, and a wagon-top supported by all the said uprights, substantially as set forth.

2. The combination, with a wagon-body provided with a top, and uprights which support the top; of spring curtain-rollers journaled in the said uprights at the sides of the wagon-body, intermediate uprights provided with curved portions to clear the said rollers, and a spring-curtain journaled in the uprights at the rear of the wagon-body under the end portions of the aforesaid rollers, substantially as set forth.

In testimony whereof I affix my signature in presence of two witnesses.

JOHN V. MACDONALD.
